(57) **CLAIM**

The ornamental design for a table lamp, as shown and described.

DESCRIPTION

FIG. 1 is a front and top perspective view of a table lamp, showing my new design ;
FIG. 2 is a rear and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is another perspective view showing the table lamp in an extended state of use; and,
FIG. 10 is another perspective view showing the table lamp in a collapsed position.
The broken lines in the figures illustrate portions of the table lamp that form no part of the claimed design.

1 Claim, 10 Drawing Sheets
